UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

SIDE-BOLT CONSTRUCTION.

Application filed November 14, 1925. Serial No. 68,967.

This invention relates to percussive rock drills but more particularly to means for assembling the different elements in a rock drill in such a way that a great rigidity can be secured and vibration and jar absorbed while at the same time no excess strain is placed on the coil springs used for this purpose. Heretofore, with the customary assembly by means of side bolts and coil springs, the springs have been subjected to unduly great compression strains and frequent breakage of the said springs results when the drills are put in operation.

The object of my invention therefore is to provide means whereby the coil springs and side bolts can be compressed to a certain point after which they are protected from any additional strain by means of a sleeve or buttress which fits over the side bolts. At the same time the springs are allowed to remain unhampered when absorbing the shock due to the downward blow of the hammer piston of the rock drill. My invention consists of the features of novelty and the combinations of elements substantially as described in this specification, set forth in the appended claims, and illustrated in the accompanying drawings in which,

Figure 1 is a side view of a rock drill partly in vertical section and partly broken away showing the invention applied thereto, and

Figure 2 is a transverse sectional view on the line 2—2 of Figure 1 looking in the direction of the arrows.

Referring to the drawings, the back head A, the cylinder B and the front head C of a percussive rock drill are shown held in fixed relation to each other by means of the side bolts D, the coil springs E and lock nuts F which parts cooperate with the usual lugs G, H and J on said back head, cylinder, and front head respectively. The lugs G and H are bored so that the side bolt D will have a substantially close fit therein. The lugs J are bored to a larger diameter than the bores of the lugs G and H in order to allow the side bolts D and sleeves K to fit slidably within the bore. Each sleeve K is of a form substantially as shown in Figure 1 of the drawing, being a cylinder open at both ends with a bore enabling the side bolt D to fit slidably within it and an outside diameter such that it will fit slidably within the bore in a lug J but will abut against the front

face of a lug H. A head or circular abutment L is on the other end of the sleeve such that the forward end of the coil spring E will abut against it. The coil spring E is of the usual design, but the inside diameter is such that it will fit over the sleeve K. An important element of the invention resides in the relative length of the sleeve K which must be determined by the amount of compression it is desired to give the coil spring E. The assembly of the device on a percussive rock drill is also substantially as shown in the drawings. After the back head A, cylinder B and front head C have been fitted together the side bolts D are run through the lugs G and H while the sleeves K with the coil springs E are run over the side bolts D from the other end and the sleeves themselves are run through the lugs J. The customary lock nuts and washer F are then screwed on the end of the side bolts D and are drawn up against the compression of the springs E until the ends of the sleeves K abut against the front faces of the lugs H. When this has occurred, the springs E can not be compressed any further and remain thus positively protected so long as the assembly remains in good condition. On the other hand the function of the springs E as cushioning means in order to absorb the vibration and jar of the rock drill when in operation, is nowise impaired. I am not to be understood as describing specifically the exact and precise means of applying my invention to percussive rock drills but merely a preferential method of application and assembly, said application and assembly always to be modified by the type of drill or by its intended use.

I claim:

1. An improvement in the side bolt assembly of a percussive rock drill comprising a sleeve adapted to fit over a side bolt and to be held between lock nuts on the end of the side bolt and lugs on the cylinder, a coil spring adapted to fit over the said sleeve, and to be carried wholly by the said sleeve, and means whereby the said spring can be compressed to a predetermined point after which the compression strain is assumed wholly by the lugs formed on the cylinder and the cylinder back head.

2. An improvement in the side bolt assembly of a percussive rock drill comprising a sleeve adapted to fit over a side bolt and to

be held in place by lock nuts on the front end of the side bolt, a coil spring adapted to fit over the said sleeve and to be carried wholly by the said sleeve, an abutment at the front end of said sleeve for the front end of said spring, a bearing between the rear end of said sleeve and the cylinder lug, and an abutment between the rear end of said spring and the front head lug, whereby the said coil spring is protected from undue compressional stress by means of the said sleeve.

3. An improvement in the side bolt assembly of a percussive rock drill comprising lugs on the back head, cylinder and front head of said percussive rock drill, a side bolt in engagement with the said lugs, a sleeve adapted to fit over the said side bolt and to be carried wholly on said side bolt, lock nuts on the said side bolt holding the said sleeve in place, a bore in said front head lug of sufficient diameter to allow the said sleeve to slidably extend through the

said bore, a bore in said cylinder lug of smaller diameter sufficient only to allow the said side bolt to fit therein, a coil spring adapted to be carried wholly by the said sleeve, an abutment on the said sleeve at its forward end for engagement with the said coil spring, the front end of the said front head lug forming a stop for engagement with the other end of said spring, and the forward end of the said cylinder lug forming a stop for engagement with the rearward end of said sleeve, the sleeve being of sufficient length to limit compression of the coil spring whereby the sleeve will permit compression of said spring against the front head lug until a predetermined compression is reached whereupon the rearward end of the said sleeve will abut against the said cylinder lug and transmit any additional strain to the said cylinder lug.

In testimony whereof I have signed this specification.

EARL B. LEAR.
